UNITED STATES PATENT OFFICE.

GUSTAVO VINCON, OF TURIN, ITALY.

AUTOMATIC FIREARM.

Application filed April 23, 1923. Serial No. 634,071.

To all whom it may concern:

Be it known that I, GUSTAVO VINCON, a subject of the King of Italy, residing at Turin, in the Kingdom of Italy, have invented certain new and useful Improvements in Automatic Firearms, of which the following is a specification.

The present invention has for its object a pneumatic retarding device for automatic firearms by the aid of which the speed at which the weapon is fired can be varied within wide limits.

The device which forms the subject matter of the invention is essentially characterized by a gripper or other device for holding the striker pivoted to a piston working in a cylinder the base of which has ports in it (controlled by a needle or other valve operated from outside) which regulates the admission of the air to the chamber of the cylinder during the suction stroke of the piston, which stroke is produced by the spring of the striker. An automatic valve permits the escape of the air contained in the chamber of the cylinder during the compression stroke of the piston, which stroke is produced by the striker in its final recoil stroke. The jaws of the gripper are also subjected to the action of a spring which tends constantly to open them and to the action of external guides which keep them closed so as to retain the head of the striker during the stroke of the piston. A front chamber permits of the opening of the jaws of the gripper at the end of the forward stroke.

It is obvious that by opening more or less the ports by which the cylinder communicates with the outer air by the aid of a suitable controlling device, the air will be allowed to enter more or less rapidly into the interior of the cylinder and the striker will be allowed to advance more or less slowly until the guides of the gripper permit it to open and the striker to pursue its forward course under the action of its own spring.

The accompanying drawing shows by way of example a constructional form of the device forming the subject matter of the invention applied to a machine gun.

Figure 1 is an axial section of the rear part of the weapon, the striker being held by the gripper and being shown in its position of maximum recoil.

Figure 2 is shown a view similar to Figure 1, but with the striker disconnected

from the gripper and shown at the moment when it accomplishes its operative forward movement.

1 is the frame of the weapon to the rear part 1' of which is screwed axially a part 1" provided internally with the guides 12 which compel the gripper to close, and with a front chamber 13 which allows the gripper to open and release the striker after having accomplished a portion of its stroke forwards, during which stroke the gripper holds the striker.

On the part 1" is screwed or fixed in any other manner, the cylinder 8, the base of which is provided with ports 19 for the admission of air controlled by the needle valve 20. In the cylinder 8 there operates a piston 7 which is provided with a stirrup or the like 7' carrying a pivot 9 on which are pivoted the jaws 10 of the gripper, which jaws are subjected to the action of a spring 11, which tends constantly to open them. To the stirrup 7' is fixed a cross piece 21 arranged between the ends of the jaws of the gripper (so as to permit this latter to close on the head of the striker), the said cross piece being intended to receive the blow of the striker head when the striker recoils, and consequently to carry the piston 7 with the gripper to the rear.

2 is the breech block of the weapon and 3 is the safety device for the striker which prevents the head of the striker from penetrating into the barrel receiving the cartridge from the breech block if this is not completely closed.

4 is the striker proper provided at the rear with a head 4' of such a shape and dimensions that it engages with the jaws 10 of the gripper of the retarding device.

The piston 7 is provided with an exhaust valve for air (formed by holes 15 against which bears the ring 16 subjected to the action of a spring) permitting of the free escape of the air from the chamber 17 of the cylinder 8 during the rearward movement (compression stroke) of the piston 7. During the forward movement produced by the spring 4" of the striker 4 the valve of the piston keeps closed and the vacuum produced in the chamber 17 opposes the return forwards of the striker, the speed of advance of which can consequently be regulated by opening more or less the admission ports 19 for air to the chamber 17 by means of the needle valve 20.

The ports 18 in the cylinder serve to re-establish atmospheric pressure in the chamber 17, when the gripper in its forward movement penetrates into the chamber 13 and opens and releases the striker.

At the moment of firing the striker recoils (with the breech block and the part 3) and, towards the end of its recoil movement, hits against and carries with it the cross piece 21 secured to the piston 7 (while the gripper with its jaws open is in the chamber 13) thus effecting the backward movement of the piston. The jaws 10 of the gripper then close and seize the head 4' on the striker when said jaws pass over the guides 12.

The return forwards of the striker is regulated as is mentioned above, by the degree of opening of the ports 19 for the part 20 of its stroke during which the jaws 10 of the gripper are held closed by the guides 12. As soon as the gripper is brought into the chamber 13, the jaws 10 open (see Figure 2) and the striker can freely execute its forward movement.

The device forming the subject matter of the present invention is of small dimensions. It permits the speed at which the weapon is fired being varied within wide limits, is 30 of very simple construction and offers great security of working. In the case of deterioration of the device it can be immediately removed by unscrewing the cylinder 8 and withdrawing the piston from it, the weapon 35 remaining always ready for action.

I claim as my invention:—

1. A pneumatic retarding device for automatic firearms, comprising a gripper or other device for gripping or holding the striker, pivoted to a piston working in a cylinder, the base of which is provided with ports controlled by a needle or other valve operated from outside and serving to regulate the admission of air to the chamber of the cylinder during the suction stroke of the piston, which stroke is produced by the spring of the striker, an automatic valve permitting the escape of the air contained in the chamber of the cylinder produced by the striker in its final recoil movement, the jaws of the gripper being subjected to the action of a spring which tends constantly to open them and to the action of external guides which keep them closed so as to hold the head of the striker during the compression stroke of the piston and a front chamber permitting the opening of the said jaws at the end of the forward movement.

2. A pneumatic retarding device for automatic firearms according to claim 1, in which the cylinder is fixed coaxially with the striker and the piston working in the cylinder carries a stirrup to which is pivoted the gripper, and a front cross piece passing between the ends of the gripper so

as to permit of the closing thereof on the lug of the striker, the said cross piece receiving the blow of the striker on recoiling and permitting the piston to be carried to the rear.

3. A pneumatic retarding device for automatic fire arms, comprising a cylinder, a piston working therein, means for effecting a controlled admission of air to the cylinder behind the piston, means for exhausting the air from behind to in front of the piston, a striker, a detent carried by the piston for engagement with the striker, means for automatically effecting such engagement at a predetermined point in the recoil stroke of the striker to cause a movement of the latter and the piston as a unit during the remainder of said stroke, a spring for effecting the firing stroke of the striker and for initially moving the piston forward with the striker, and means for automatically disengaging the detent at a predetermined point in said firing stroke to enable the striker to complete the stroke alone; substantially as described.

4. In an automatic fire arm, the combination, with a recoil-operated striker and a spring for effecting the firing stroke thereof, of a piston associated with the striker, means for automatically coupling the piston and striker together for movement as a unit after the striker has commenced its recoil stroke, a pneumatic device associated with the piston for adjustably retarding its movement with the striker during the initial portion of its firing stroke, and means for automatically uncoupling the striker from the piston at a predetermined point in said firing stroke to enable it to complete the stroke alone.

5. In an automatic fire arm, the combination, with a recoil-operated striker and a spring for effecting the firing stroke thereof, of a cylinder, a piston working therein, means for automatically coupling the piston and striker together for movement as a unit after the striker has commenced its recoil stroke, means for regulating the admission of air to the cylinder behind the piston to adjustably retard the speed of said piston and striker during the initial portion of the firing stroke of the striker, and means for automatically uncoupling the striker from the piston at a predetermined point in said firing stroke to enable it to complete the stroke alone.

6. In an automatic fire arm, the combination, with a recoil-operated striker and a spring for effecting the firing stroke thereof, of a piston, a detent carried by the piston and comprising a pair of coacting jaws, means for automatically closing said jaws against the striker at a predetermined point in the recoil stroke of the striker to cause a movement of the latter and the piston as a unit during the remainder of said stroke, and means for effecting an automatic open-

ing of the jaws and consequent disengagement of the striker at a predetermined point in its firing stroke to enable said striker to complete the stroke alone.

- 5 7. In an automatic fire arm, the combination, with a recoil-operated striker and a spring for effecting the firing stroke thereof, of a piston, a detent carried by the piston and comprising a pair of coacting jaws, 10 means for automatically closing said jaws against the striker at a predetermined point in the recoil stroke of the striker to cause a

movement of the latter and the piston as a unit during the remainder of said stroke, means for effecting an automatic opening of 15 the jaws and consequent disengagement of the striker at a predetermined point in its firing stroke to enable it to complete the stroke alone, and a pneumatic device for adjustably retarding the unitary movement 20 of the piston and striker during said firing stroke.

In testimony whereof I affix my signature.

GUSTAVO VINCON.
